United States Patent Office.

GEORGE A. MOSHER, OF CHAMPLAIN, NEW YORK.

Letters Patent No. 81,669, dated September 1, 1868.

IMPROVEMENT IN DRAUGHT-EQUALIZER.

The Schedule referred to in these Letters Patent and making part of the same.

TO ALL WHOM IT MAY CONCERN:

Be it known that I, GEORGE A. MOSHER, of Champlain, in the county of Clinton, and State of New York, have invented a new and useful Improvement in Draught-Equalizing Double-Tree; and I do hereby declare that the following is a full, clear, and exact description thereof, which will enable others skilled in the art to make and use the same, reference being had to the accompanying drawings, forming part of this specification, in which—

Figure 1 is a perspective view of my invention.

Figure 2 is a diagram illustrating the principle of its operation.

Similar letters of reference indicate like parts.

The object of this invention is to enable two horses of unequal strength or energy to be worked together with the best results.

It is difficult to obtain a pair of horses which are perfectly matched with respect to endurance, strength, and spontaneity of effort, and this unequal condition renders the weaker one, when both are working together, to sustain more than its proper share of the draught-strain when the ordinary double-tree is used. If one is more spirited, the same result is obtained, and my invention is designed to obviate these objectionable conditions.

It consists of the usual bar or double-tree A, pivoted to the tongue B, but is provided with cross-heads C, which cross-heads have a number of holes, *a*, *b*, &c., for the purpose of pivoting the clevises D D thereto.

The single-trees are attached to these clevises, which are pivoted at different points by pins. In the drawings, two pins are shown, but in practice, both pins are not used in each clevis at once, unless the horses are very imperfectly matched with regard to endurance, strength, and working energy.

If the horses are equally free, but of unequal endurance, the weaker one will naturally fall behind, and by attaching the clevis of the weak horse rigidly with both pins, and pivoting the clevis of the stronger one to the front end of the cross-head, or approximating thereto, according to the excess of his energy, the leverage will then be in favor of the lagging horse, as is evident from the diagram, in which E is the front of attachment of the lagging horse, and G that of the more enduring one. The lines *m m* and *n n* exhibit the relative difference of leverage.

When the horses are unequally free, and the freer horse is less enduring than the other, the leverage is to be in favor of the forward horse, which is provided by pivoting both clevises at the rear ends of the cross-heads, as illustrated by the lines D D, in the diagram. The relative difference of leverage is shown by the lines *f f* and *g g*.

When the freer horse is more enduring than the other, the clevis should be pivoted as in the first case.

The clevises are provided with a series of holes to correspond to those in the cross-heads.

In the diagram, the angle which the double-tree makes with the tongue or line of draught B, is exaggerated, that the difference may more readily be seen by inspection.

The extreme cases have been taken also with reference to the pivoting of the clevises, but in practice it may be only necessary to pivot one clevis only a short distance from the double-tree or line of equal draught A, as indicated by the line H.

The elongated heads of the double-tree may be obtained by means of cross-heads C C, braced, as shown, or by any other suitable elongation, at right angles to the double-tree.

The clevises may also be made of any suitable form.

A legitimate modification of my invention would be the employment of a single cross-head at the middle point of the double-tree, with a series of holes to bolt it to the tongue.

This form would dispense with the cross-heads at the ends, and in some respects be more advantageous.

Having thus described my invention, I claim as new, and desire to secure by Letters Patent—

The clevises D, constructed as described, and provided with a series of holes, *b*, adapted for the passage of a pin, *a*, whereby said clevises are pivoted to the cross-pieces C of the centrally-pivoted double-tree A, so as to be longitudinally adjustable thereon, as set forth.

G. A. MOSHER.
